INVENTOR.

James F. Thayer

UNITED STATES PATENT OFFICE.

JAMES F. THAYER, OF PROVIDENCE, RHODE ISLAND.

BUTTON-FASTENER.

SPECIFICATION forming part of Letters Patent No. 358,507, dated March 1, 1867.

Application filed December 4, 1886. Serial No. 220,675. (No model.)

To all whom it may concern:

Be it known that I, JAMES F. THAYER, a citizen of the United States, residing at Providence, in the county of Providence and State of Rhode Island, have invented certain new and useful improvements in Button-Fasteners; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My present invention relates to a new and useful improvement in button-fasteners styled "staples;" and it consists, primarily, of a wire fastener comprising a central button-loop cylindrical in form, a flattened portion 20 on each side thereof, and two cylindrical attaching-prongs with sharpened or attenuated points, said fastener adapted to be used in connection with an eye shank button or to be combined with a head portion rigidly secured 25 to the central button-loop, all as will be hereinafter more fully described.

Figure 1 is a perspective view of my improved fastener. Fig. 2 is a like view of the same with an eye-shank button as secured to fabric. Fig. 3 represents my improved fastener combined with a head portion rigidly secured thereto.

In forming the fastener round wire is preferably employed. It is first cut to a given 35 length and manipulated by proper machinery, which bends and swages the wire into the required shape. The central portion of the wire is bent to form the button-loop 1 for the reception of the button. On each side of said 40 button-loop the wire is rolled or broadened to form bearings or flattened portions 22, terminating in downwardly-projecting prongs 33, bent at right angles to said flattened portions, said prongs being provided with sharpened or 45 attenuated points, the button loop and prongs being cylindrical in form, or of the form or configuration in cross-section as the wire from

which the fastener is made, as fully shown in Fig. 1 of the drawings.

In securing a button to fabric, the wire eye-shank is passed sidewise onto one of the prongs 3, and over the flattened portion 2, to take advantage of the elongated shape of said button-eye shank, which allows the flattened portions to be broadened considerably wider than the wire from which the fastener is made. When the central loop is reached, the button is turned upright and the fastener is secured to fabric, as shown in Fig. 2, the flattened portions 22 forming a firm bearing on the upper 60 surface, the cylindrical form of the central loop enabling the button to move freely in all directions, while the cylindrical prongs, with sharpened or attenuated points, allow an easy penetration and a secure clinch in the fabric. 65

By forming the central button-loop, 1, a trifle longer than is required for an eye-shank button, the fastener may be provided with a head portion, 4, rigidly secured thereto by compressing or molding upon said central button-loop, thus making a desirable combined 7c button and fastener, as shown in Fig. 3 of the drawings.

Having described my invention, I claim—

1. A button - fastener comprising a central button-loop cylindrical in form, a flattened portion on each side thereof, and two downwardly-projecting cylindrical attaching-prongs with sharpened or attenuated points, as set forth. 75
2. The button - fastener herein described, 80 consisting of a central button-loop cylindrical in form, a flattened portion on each side thereof, and two cylindrical attaching prongs with sharpened or attenuated points, in combination with a button-head rigidly secured to the 85 central button-loop of said fastener, substantially as and for the purpose specified.

In testimony whereof I affix my signature in the presence of two witnesses.

JAMES F. THAYER.
